(57) **CLAIM**

We claim the ornamental design for a sequencing instrument, as shown and described.

DESCRIPTION

FIG. 1 is a front, right top perspective view of a sequencing instrument illustrating our new design;

FIG. 2 is a front, right bottom perspective view of the design of FIG. 1;

FIG. 3 is a front, left top perspective view of the design of FIG. 1;

FIG. 4 is a front, left bottom perspective view of the design of FIG. 1;

FIG. 5 is an enlarged partial, front, right top perspective view of the design of FIG. 1;

FIG. 6 is an enlarged partial, front, left top perspective view of the design of FIG. 1;

FIG. 7 is an enlarged partial, front, right bottom perspective view of the design of FIG. 1;

FIG. 8 is an enlarged partial, front, left bottom perspective view of the design of FIG. 1;

FIG. 9 is an enlarged partial, front, top perspective view of the design of FIG. 1;

FIG. 10 is an enlarged partial, front, bottom perspective view of the design of FIG. 1;

FIG. 11 is a rear, left top perspective view of the design of FIG. 1;

FIG. 12 is a rear, left below perspective view of the design of FIG. 1;

FIG. 13 is a rear, right top perspective view of the design of FIG. 1;

FIG. 14 is a rear, right bottom perspective view of the design of FIG. 1;

FIG. 15 is a front elevational view of the design of FIG. 1;

FIG. 16 is a right side elevational view of the design of FIG. 1;

FIG. 17 is a left side elevational view of the design of FIG. 1;

FIG. 18 is a rear elevational view of the design of FIG. 1;

(Continued)

FIG. 19 is a top plan view of the design of FIG. 1; and, FIG. 20 is a bottom plan view of the design of FIG. 1. The even length broken lines shown in the drawings illustrate portions of the sequencing instrument that form no part of the claimed design. The dot-dash cutaway lines shown in FIGS. 5 through 10 represent the boundaries of the enlarged views and form no part of the claimed design. The dash-dot lines in the drawings represent a boundary of the claimed design.
